UNITED STATES PATENT OFFICE.

ALONZO W. MINOT AND MARTIN RHOADES, OF ROCKFORD, ILL., ASSIGNORS
TO HENRY H. PALMER AND GEORGE E. KING, OF SAME PLACE.

CHURN.

SPECIFICATION forming part of Letters Patent No. 253,879, dated February 21, 1882.

Application filed October 7, 1881. (No model.)

To all whom it may concern:

Be it known that we, ALONZO W. MINOT and MARTIN RHOADES, citizens of the United States, residing in the city of Rockford, in the county of Winnebago and State of Illinois, have invented a new and useful Improvement in Churns, of which the following is a specification.

Our invention relates to that class of churns known as "end-over-end revolving churns." It however relates more particularly to the ring-head and removable lid employed in this class of churns.

The object of this invention is to improve the removable lids to render them more efficient in their connection with the ring-head. To this end we have devised and constructed the ring-head and removable lid represented in the accompanying drawings, in which—

Figure 1 is a plan view of a ring-head and removable lid embodying our invention, of which Fig. 2 is a central section cut on a plane passing lengthwise centrally through the radial endwise-sliding bolts. Fig. 3 is a plan view of the ring-head and removable lid with the spirally-grooved cam and radially-sliding bolts omitted. Fig. 4 is an under face view of the spirally-grooved cam, and Fig. 5 is an isometrical representation of one of the radial sliding bolts.

In the figures, A represents a metallic ring-head, having its outer edge, *a*, reduced to proper form to enter a groove or croze formed in the inner side of the end portion of a barrel-formed vessel, to be held therein by means of hoops, in the usual manner. This annular ring-head, on its inner edge, is formed with an uprising rim or bead, *b*, designed to receive a suitable packing of a removable lid.

At *c* are represented ears, which rise in a vertical position from the outer surface of the annular ring-head, and are produced in pairs at proper intervals. Each pair of these vertical ears is provided with a roller, *d*, placed between their upper or outer end portions, supported to revolve on a transverse pin or shaft, *e*, passed transversely through the ears and through the axial center of the rollers in such a manner that the rollers will revolve on their central support.

At C is represented a metallic annular ring

of angle-iron form in section, consisting of a horizontal flange, *h*, and a vertical rim or flange, *i*, the diameter of which is such as to overreach the uprising rim or bead *b* of the annular ring-head. The horizontal or disk portion *h* of this ring is formed at proper intervals with inward projections, *k*, perforated to receive screws; and it is also provided at proper intervals—in this instance to correspond with the inward projections—with uprising guide-ears *l*, perforated to receive suitable endwise-moving bolts to slide therein freely.

At D is represented a lid—in this instance of wood in disk form—of suitable diameter to be received within the vertical flange *i* of the annular ring C snugly, and is fixed in place by means of suitable screws or rivets inserted through the perforated inward projections, *k*, and into or through the wood disk. The under outer edge portion of this disk-lid is rabbed, as represented at *m*, in which groove is inserted a suitable annular packing-ring, *n*—in this instance made from cork—which, when the lid is in place on the ring-head, will engage the uprising bead *b* on the inner edge of the ring-head.

At E is represented a metallic spider, consisting of the annular ring *o*, having the cross-arms *o'* connecting its inner edges. The outer edge of the annular rim of this spider is formed with an uprising rim, *o''*, in nearly quarter-sections, leaving an open space, *o'''*, between their ends opposite the ends of the radial cross-arms of proper width to receive the radial endwise-sliding bolts, and, in connection with the uprising perforated ears *l*, serve as guides to give direction to the radial endwise-sliding bolts. The radial cross-arms of this spider on one side of their outer end portions are provided with a flange, *o⁴*, which rises above the plane of the arm and receives the sidewise pressure of the bolts produced by the action of the spirally-grooved operating-cam. This spider is provided with a central tubular hub, *o⁵*, rising from its outer surface, and adapted to receive a suitable bolt. This spider is centrally fixed to the outside of the wood disk-head by means of screws in such position that its radial arms will be in line radially with the perforated uprising guide-ears *l*.

At F are represented the radial endwise-slid-

ing bolts, which are of bar form, rectangular in section, adapted to enter and slide endwise in the guide-ears *l*. The inner end portion of these bolts, as at *p*, is reduced in thickness, and is of a proper width to enter the openings *o* in the uprising outer rim of the spider. The extreme inner ends of these bolts are provided with an uprising stud-arm, *p'*, adapted to enter a spiral groove in an operating-cam. The outer end portions of these bolts are beveled on their upper sides, as at *p''*, in an inclined wedge form to enter between the vertical ears *c* of the annular ring-head, and under the rollers *d*, journaled therein.

At *H* is represented a dish having a diameter about equal to the diameter of the spider *E*, and is provided with a spiral thread, *s*, rising from its under side and extending from near its center in parallel spiral lines to near its periphery, forming a spiral groove, *s'*, which receives the uprising studs *p'* on the inner end of the bolts. This spirally-grooved disk is provided with a central opening to receive the tubular hub *o* of the spider in such a manner that the spiral thread *s* will be within the outer rim, *o*, of the spider, and the spiral groove *s'*, formed by the spiral thread, will receive the studs *p'*.

At *t* is represented a screw-bolt, which is passed upward through the wood disk of the lid, through the tubular hub of the spider, and through a washer, *t'*, to receive a screw-nut, *t''*, by means of which the parts are firmly clamped to each other and in such a manner as to hold the spirally-grooved cam in position to revolve on the tubular hub of the spider.

At *u* are represented lever arms or handles, rising and extending outward from the outer upper angle of the spirally-grooved disk, by means of which the disk may be rotated.

From the foregoing it will be seen that with the removable lid placed on the annular ring-head in such position that the outer ends of the radially-sliding bolts will be opposite the

rollers in the ears rising from its outer surface 45 a rotary movement of the spirally-grooved cam-disk toward the right hand will cause the bolts to move outward and their outer wedge-formed ends to pass under the rollers, which action will force the annular packing-ring against the 50 uprising rim or bead on the inner edge of the annular ring-head, operating to produce a tight-fitting lid, and the turning of the cam-disk toward the left hand will operate to retract the bolts and permit the removal of the lid. 55

By the employment of the rollers in the uprising ears of the annular ring-head to receive the wedging ends of the bolts we greatly reduce the friction of the parts and produce a better result with a less expenditure of power, 60 and prevent the cutting action or severe wear-ing of the parts.

We claim as our invention—

1. The combination, with an annular ring-head, of anti-friction rollers supported to revolve on bearings above the surface of the annular ring-head, substantially as and for the purpose hereinbefore set forth. 65
2. The combination, with an annular ring-head provided with anti-friction rollers mounted to revolve on bearings above the surface of the annular ring, of a removable lid provided with radially-moving bolts to engage the anti-friction rollers, substantially as and for the purpose hereinbefore set forth. 70
3. The combination, with an annular ring-head provided with anti-friction rollers mounted to revolve on bearings above the surface of the annular ring, of a removable lid provided with radially-moving bolts, operated by a spi- 75 rally-grooved rotary cam, substantially as and for the purpose hereinbefore set forth. 80

ALONZO W. MINOT.
MARTIN RHOADES.
